UNITED STATES PATENT OFFICE.

LOUIS O. LIEBER, OF LOS ANGELES, CALIFORNIA.

UNIVERSAL RECEPTACLE.

1,231,760.

Specification of Letters Patent. Patented July 3, 1917.

Application filed February 23, 1916. Serial No. 79,919.

To all whom it may concern:

Be it known that I, LOUIS O. LIEBER, a citizen of the United States, residing at Los Angeles, in the county of Los Angeles, State 5 of California, have invented new and useful Improvements in Universal Receptacles, of which the following is a specification.

This invention relates to receptacles and the like such as are used in electrical construction; and it is the object of this invention to provide a receptacle which shall be universal in its use, and be capable of receiving any of the ordinary forms of plugs and also a special form of plug here- 15 inafter explained.

It is an object of this invention to provide a construction which will lead to cheapness of manufacture, both of the receptacle and of the plug, lamp base, or the like, receiv- 20 able by the receptacle. In almost any situation where a receptacle is used, and particularly in situations such as obtain in fuse blocks, electrically lighted signs and various other pieces of apparatus, the number of 25 plugs or lamps with bases used is very large. For instance, in an electrically lighted sign the lamps are replaced from time to time; and this is also obviously true of the fuse plugs in a fuse block. It is an object of 30 this invention to simplify the construction of the plugs or bases themselves, so as to reduce as far as possible the cost of those parts of which the greatest number is used.

Further objects of this invention, and a 35 preferred form of structure embodying the invention, are explained in the following specification, reference being made to the accompanying drawings, in which Figure 1 is a section showing my improved universal 40 receptacle in use as in an electric sign or the like, Fig. 2 is a section taken as indicated by line 2-2 on Fig. 1, Fig. 3 is an enlargement of a part of the showing of Fig. 1. Fig. 4 is a view similar to Fig. 1 showing my 45 receptacle receiving an ordinary screw base lamp, Fig. 5 is a section showing the application of my invention to a fuse plug, and Fig. 6 is a view showing a form of fuse plug with a plain instead of a screw- 50 threaded shell.

In the drawings I have shown a receptacle comprising a cylindrical shell 10, which shell has a circumferential slot 11 in which a ball 12, or equivalent number, is 55 adapted to move. This ball 12 rolls against a surface 13 back of the slot 11, the ball pro-

jecting through the slot into the interior of the shell 10. The surface 13 is formed by the inner face of a suitable member 14, which member may be made integrally with the 60 shell 10, although this is not an essential. The surface 13 is eccentric to the shell 10; so that when the ball is at one end of the slot 11 it projects considerably past the inner surface of shell 10; while, when the 65 ball is at the other end of the slot 11, it projects but little past the surface. In the various views the ball is shown in its position of greatest projection. The slot 11 is of such width, that, although the ball 70 may project as is best shown in Fig. 3, the ball cannot fall entirely through the slot, being restrainingly carried by the shell 10 in the manner described.

The shell 10 is mounted upon and within 75 a suitable member 20, usually of porcelain or the like, the usual connecting screws 21 and 22 being provided for the electrical connections, screw 21 being electrically connected with the shell 10, and screw 22 with 80 the central spring contact 23. This central spring contact may be made in any form desired, but preferably resilient so that the plug may be moved inwardly to its proper position and make good contact with the 85 member 23. The central contact 25 of a lamp base, plug or the like, engages with central contact 23; while the exterior shell 26 of the plug, lamp base or the like, contacts with the shell 10. The plug or base 90 shell 26 has preferably a slight circumferential groove 27 which comes opposite the ball 12 when the plug or base is inserted. The plug or base is inserted and is turned slightly to the left (in Fig. 2) so as to roll 95 the ball 12 back to the left hand end of slot 11. The ball then projects by the minimum amount and the plug or base may then be pushed back into the receptacle until it reaches the bottom of the receptacle. The 100 plug or base is preferably fairly loose in the receptacle shell 10 so as to be easily and quickly inserted and withdrawn. When the plug or base has been fully inserted it is simply turned a short distance in a right 105 handed direction and the ball 12 is rolled back toward and to the position shown in Fig 2 by frictional contact with the plug, the eccentric surface 13 forcing the ball toward the plug or base into the position 110 shown in the various views. The plug or base is then held against longitudinal re-

moval; but it will be seen that a slight rotation in a left handed direction is always sufficient to release the plug or base so that it may be immediately withdrawn. It is 5 one of the features of this invention that a plug or lamp may be very quickly removed from the receptacle without rotation of more than a fraction of a revolution. And it is a feature of this invention, that the lamp, 10 plug, or the like, is easily removed. This is in distinction to the sometimes difficult removal of sign lamps where the lamp often corrodes into the socket and sticks tightly, causing the destruction of the lamp by being 15 twisted off its base.

It is also a feature of this invention that the plug or lamp base can be made in the plain and inexpensive form shown in Figs. 1, 2 or 6; and it is one of the objects of my 20 invention to provide a receptacle which will receive and hold such a plug or base. It is seen that the plug or base need not be screw threaded, but can be made in plain, cylindrical form, preferably with the slight circumferential groove 27, which groove is 25 easily made. For some purposes it is not necessary to provide the groove. The ball cannot roll longitudinally, or axially, of the cylindrical shell; so that the friction of the 30 plug or base shell with the ball will prevent the plug or base from being removed even if there is no circumferential groove.

I have shown in Fig. 4 the retention of an ordinary screw base 26^a in my receptacle. 35 It will be seen that the ball engages with the side of the thread. The action is substantially the same as with the grooved cylindrical base. My receptacle is capable of receiving any of the ordinary forms of 40 screw-threaded plugs or bases or the like.

It will be understood, of course, that my receptacle is applicable to situations other than those herein shown and explained. In 45 Figs. 1 and 2 I have shown my receptacle as applied to sign work. In such work the member 20 is usually placed behind the background board or the like 30, the receptacle shell 10 projecting through an aperture in the member 30. The forward end of 50 the receptacle shell 10 is provided with a flange 31 which is formed spirally, in the form of a single convolution of thread, so as to be engageable by screw threads 32 on the cap 33. Cap 33 bears back against the member 30 and a gasket or washer 34 may be inserted to make a weather tight joint between the cap 33 and member 30. In the

form shown in Fig. 1 I have also shown the lamp base shell 26 provided with a flange 35 under which a washer or gasket 36 is 60 held, said washer or gasket pressing back against the cap 33 so as to make a weather tight joint between the lamp base and the cap. In this manner a totally weather tight joint is made which completely protects the 65 receptacle from deterioration.

In Fig. 5 I have shown the adaptation of my invention to a fuse block 40. The receptacle shell 10 is provided with a ball 12 rolling in the slot and against the eccentric 70 surface as hereinbefore explained. The central contact 23 may be of any desired character. This receptacle will, as hereinbefore explained, take a screw thread plug 26^b or it will take a plug of the form shown in Fig. 75 6. The plug shown in Fig. 6 has a plain cylindrical shell 26 preferably with the circumferential groove 27 and has the central end contact 25. A fuse plug of this character is more cheaply constructed than the 80 ordinary screw thread plug; and on account of the very large number of these plugs used, the saving in cost of manufacture is of very great importance.

Having described my invention I claim: 85

1. An electrical connector, comprising a cylindrical receptacle and a cylindrical plug adapted for free and independent longitudinal movement and rotation in said receptacle, said receptacle having a circumferential 90 slot with an eccentric surface back of the slot, and a ball restrainingly carried by said receptacle adapted to move on said eccentric surface and project through the slot inwardly into the interior of the receptacle to 95 be engaged by the plug.

2. An electrical connector, comprising a cylindrical receptacle and a cylindrical plug adapted for free and independent longitudinal movement and rotation in said receptacle, a rolling member mounted on and carried by the receptacle and projecting inwardly into its interior for engagement by the plug, and means to cause movement of said member inwardly against the plug by 100 105 virtue of rotation of the plug in the receptacle.

In witness that I claim the foregoing I have hereunto subscribed my name this 17th day of February 1916.

LOUIS O. LIEBER.

Witness:

JAMES T. BARKELEW.
